ARROW FOR ARCHERY

Robert H. Cowdery, Geneva, Ohio, assignor to
The American Fork & Hoe Company, Cleve-
land, Ohio, a corporation of Ohio

Application August 1, 1930, Serial No. 472,449

4 Claims. (Cl. 273—106.5)

My invention relates to arrows for archery, and relates more particularly to the provision of arrows adapted to be used for target and hunting purposes, and which may be produced in quantities with uniformity in the qualities of weight, balance, and straightness as well as having uniform air friction effects.

Heretofore, arrows have been made of many different materials, and efforts have been made to accomplish the production of an arrow metallic in whole or in part, and in which one or more of the above qualities was sought to be obtained.

These efforts have left much to be desired in the effort for achievement of all of the above qualities in an arrow responding to the requirement of present day practice.

For instance, at the present time an arrow adaptable for competitive target, clout and distant shooting, is usually about 28 inches long and 20 may weigh the equivalent of 4 shilling and 9 pence in new English silver, and the "bob-tail" comprises three feathers each curving the same way and usually about 1½ inches long and ½ inch deep, and preferably are made of seasoned 25 red deal and although these may be "self" very often are "footed"; that is, a piece of hard wood to which the pile or point is attached is spliced to the deal shaft, which of course must be perfectly straight and stiff. This construction involves the making of the shaft to a uniform diameter, of approximately $\frac{3}{16}$ of an inch.

The archery associations have set up certain specifications, not differing greatly from the above, for arrows used in competitive archery, 35 but it is found very difficult to make arrows of wood or other material suitable for the purpose, adaptable to conform to such specifications, and in using deal or other seasoned wood, difficulty is had in achieving the desired straightness, weight, 40 and balance, and even more difficulty is had in obtaining the desired straightness in an arrow after making, during, and pending use. Wood is very susceptible to warping and many expedients have been adopted, such as storing the arrows in 45 a closed case, whereby all sides of the arrow are exposed to the same temperature and humidity conditions. Archers, however, are prone to disregard the safe-guards which minimize but which may not prevent warping, with the result that the 50 arrows must be carefully selected before each competition, many being thrown out as unfit, which usually costs much in production and maintenance up to the time of competition.

An object of my invention is to accomplish the 55 production of an arrow of a form capable of being

made in quantities, with substantially uniform results as to weight, balance, and a high degree of straightness, and to provide for the mounting thereon of the necessary pile, a bob-tail, and nock.

Another object of my invention is to provide an arrow having the aforesaid qualities and which will maintain such qualities through indeterminate periods of use, or non-use and without requiring the care now required to maintain arrows 5 free from warping.

Another object of my invention is to provide an arrow hardy enough to withstand the forces incidental to its use without substantial variation in form.

Other objects of my invention and the invention itself will become apparent by reference to the following description of a certain embodiment of my invention, illustrated in the accompanying drawing.

Referring to the drawing:—

Fig. 1 is an elevational view of an embodiment of my invention;

Fig. 2 is a partly cross-sectional elevational view of the embodiment of Fig. 1, such view illustrating substantially the actual size of the same;

Fig. 3 is a transverse sectional view taken on the line 3—3 of Fig. 2;

Fig. 4 is a fragmentary view mostly in longitudinal section showing another construction of the pile.

Referring to Figures 1, 2, and 3, wherein like parts are designated by like reference characters, I show a shaft 1, formed of a light tubular metal material such as a seamless tube of steel having a relatively thin wall, and a diameter sufficiently small to render the same of light weight, while at the same time of sufficient wall thickness to insure durability thereof. The diameter of the shaft is preferably of equal diameter at each end 35 of the same.

At 6 I show an impact pile telescoped over one end of the shaft 1, and at 10 I show a nock formed on the opposite end of the said shaft.

In Figs. 1 and 2 at 6 I show an impact pile preferably in the form of a bullet head and formed of hollow steel or the like having a pointed conical or otherwise tapered end which preferably has a filling of lead as hereinafter described, and shown in Fig. 3. Said impact pile 6 has a pointed end projected over the end of the tube 1, said tube 1 having an end thereof reduced in its transverse dimensions at 7, the reduced portions 8 being telescoped into the end of the pile with the shoulder 50 55

7 thereof engaging the end of the pile, the pile preferably soldered to the tube at the joint 9. My construction contemplates a sealed engagement of the tube 1 with the pile 6 at the shoulder 5 7 and the joint 9 of the tube to absolutely prevent the ingress of moisture or the like.

At 10 I show a nock formed in the end of the shaft 1 by cutting aligned U-shaped slots 11 in oppositely disposed sides therein and in bending 10 the edges of the bifurcated portions of the shaft thus formed inwardly at 12 and 13, and rounding the same at their extremities 14. The slots and rounded side portions may be machined 15 and all sharp corners and burrs may be removed during such a machining operation thereon, and accordingly the nock will not cut or fray the bow string in use.

A plug 15 of wood or other compressible material 20 may be forcibly inserted into the shaft bore 16, beyond the nock and thus form a stopper to prevent the ingress of moisture or water into the shaft and thereby eliminating the possibility of the tubular shaft rusting or deteriorating from the interior outwardly.

In Fig. 4 I have illustrated another embodiment 25 of my invention showing a pile construction which comprises inwardly swaging the end of the tubular shaft 2 at 3 to closely approximate a point 4 and in then filling the small recess remaining in the end of the tube with lead 5 or the like, to insure proper balance of the arrow and also to seal the end thereof against the ingress 30 of moisture into the shaft.

A feathering for guiding the flight of the arrow 35 during its flight through the air is provided and disposed on the end of the shaft adjacent to the nock end thereof, the feathering being secured thereon preferably by a wrapping 17 of thread, or the like, wound spirally about the shaft and covering a portion of the surface thereof, a distance of substantially $2\frac{1}{2}$ inches in length. This wrapping provides a supporting base for a plurality of feathers, preferably three in number, equally spaced from each other, the quills 18 there- 40 of being secured to the wrapped base by a suitable cement, glue, or the like adhesive material, and with the projecting ends of the quill further secured to the base by a thread spirally wound about the same and the shaft at 19 and 20. The quills 45 extend longitudinally along the shaft surface with the feather vanes 21 projecting radially thereof. Each of these vanes is naturally bent in a very slight curve in the same direction from their forward end toward their rear end and forms a screw 50 propeller which may effect rotation of the arrow during its flight through the air and thus increase its precision and projectability. However, these vanes may be so secured that the natural curvature of the same is reduced. If desired, the edges 55 of the vanes may be trimmed, as shown; however, they may be left with straight edges.

I have found that a tubular shaft having a length of 25 and $\frac{7}{8}$ inches possessing a diameter of $\frac{3}{4}$ of an inch throughout its entire length and having a wall thickness throughout its length of substantially .0075 of an inch is well adapted for use in the formation of an arrow, and I have found that an arrow having these dimensions gives highly satisfactory results. This length added to the length of pile and nock may give a desired total length of 28 inches. However, it is to be understood that I may depart from the dimensions herein given and I do not wish to

be limited to these dimensions, as they are given merely for the purpose of illustration and to impart a more thorough understanding of my invention. My completed invention is well adapted to conform to specifications in vogue promulgated by the various archery associations. 5

It can be readily seen that all possible care has been taken in my present invention to secure an arrow adapted to withstand various climatic conditions as well as the most rigorous of wear as I have provided improved means for sealing both ends of the shaft against the ingress of moisture and the like. The outer surface of the tubular shaft may also be covered with a protective coating to prevent the deteriorating effects of the elements 15 from attacking the tubular shaft from its exterior surface. A high metallic polish may be applied to the tubular shaft and thus decrease air friction of the arrow during its flight through the air, thereby increasing its range and precision. 20

Another method of fletching the arrow which may be used if preferred in the instant arrow is, as illustrated in my co-pending application for United States Letters Patent filed July 5, 1927, bearing Serial No. 203,425, of which this applica- 25 tion is a continuation in part.

It is to be understood that my invention herein relates mainly to the provision of an all-metallic arrow having an impact pile, preferably as noted above in the form of a bullet head and 30 formed of hollow steel or the like, having a pointed end projected over the reduced end of the tube, the reduced portion being telescoped into the end of the pile, and to the provision of a nock formed by the shaft and sealing an end 35 thereof.

My arrow may employ a filling as indicated in my co-pending application, referred to above, or other means to deaden any ringing metallic sound which may result in the shooting of the arrow. 40

Having thus described my invention, I am aware that numerous and extensive departures may be made therefrom but without departing from the spirit of my invention.

I claim:—

1. An arrow for archery comprising a metallic tubular shaft, and a nock slot formed in one end of said shaft, the periphery of said slot having its bifurcated edges curved inwardly.

2. An arrow having a tubular metallic shaft, a pile closing one end of the shaft, an outwardly open nock formed in the walls of the other end of the shaft, a stopper closing the nock end of the shaft inwardly of the nock.

3. An arrow for archery comprising a metallic tubular shaft, a pile on one end and a nock on the other end formed from indent portions of the tubular wall and comprising diametrically opposite generally U-shaped outwardly open notches in the end of the shaft, the closed end of the U and sides of the notches extending inwardly a substantial distance beyond the inner face of the tube walls.

4. An arrow for archery comprising a metallic tubular shaft, a pile on one end and a nock on the other end formed from indent portions of the tubular wall and comprising diametrically opposite generally U-shaped outwardly open notches in the end of the shaft, the closed end of the U extending inwardly a substantial distance beyond the inner face of the tube walls.

ROBERT H. COWDERY.
